UNITED STATES PATENT OFFICE.

CHARLES ROBERT WOOD, OF MEMPHIS, TENNESSEE, ASSIGNOR OF ONE-FOURTH TO
W. E. MOSS AND ONE-FOURTH TO B. C. GOODRICH, BOTH OF MEMPHIS, TENNESSEE.

PNEUMATIC ELEVATOR FOR ELEVATING SEED COTTON FOR GINS.

Application filed May 13, 1919. Serial No. 296,851.

To all whom it may concern:

Be it known that I, CHARLES ROBERT WOOD, a citizen of the United States, and a resident of Memphis, in the county of Shelby and 5 State of Tennessee, have invented new and useful Improvements in Pneumatic Elevators for Elevating Seed Cotton for Gins of a Ginning Plant, of which the following is a full, clear, and exact description.

10 The invention relates particularly to means whereby seed cotton as it is delivered at the ginning plant can be handled with greater economy and dispatch by reason of improved construction in the elevator and 15 its operating elements.

One of the objects of the invention is to provide a pneumatic elevator, preferably adapted for delivering the seed cotton to a number of gins, with valve means whereby 20 the operation of elevating the seed cotton will not be interrupted or the quantity of cotton being elevated diminished by reason of the choking or filling up of the delivery chute of the gins, by reason of an automatic 25 provision for an overflow of the cotton at each gin and the subsequent introduction of the overflow cotton into the gin at suitable periods in the operation of ginning, thus making the process of elevating the cotton 30 when once started continuous.

A further object is to provide an elevator of the pneumatic type that will be not only simple and durable in its construction as well as easily operated by unskilled operatives, and one that will not choke up with 35 the cotton as is now common with this type of elevator, and one that will always insure the steady flow of seed cotton and the delivery to each gin of more cotton than the 40 gin can work so as to provide for the maximum results in the operation of the gins.

To the above ends the invention consists primarily in providing in connection with the pneumatic elevator and its delivery 45 valve, means for ejecting the over-delivery of cotton from its place of accumulation about the valve, as when the gin chute becomes filled, so that the process of elevating will be continuous and in steady flow, and 50 the invention further consists in providing pneumatic means whereby the overflow of cotton from its place of ultimate accumulation at the gin, as upon the gin floor, may be

re-introduced into the elevator and delivered to the gins at such times as may be desirable. 55

Further the invention consists in the combination with the elevator, of a valve for receiving and delivering the cotton to the gin chute, that is of novel construction and operation, and in means for operating the valve 60 automatically to cause it to ultimately receive and deliver the cotton.

The invention further consists in a provision whereby the valves for the receiving and delivery of the cotton are caused to operate so as to make their discharge quickly and not synchronous with each other, so that not only is the suction never cut off in the elevator by reason of this alternating discharge, but the delivery of the cotton to the 70 valve is practically constant and the elevator is kept at maximum delivery.

The invention also consists in certain other novel features in the construction and arrangement of parts, all as hereinafter described and as pointed out in the appended claims. 75

In the accompanying drawings:

Figure 1 is a front view of the elevator.

Figure 2 is a view showing the elevator in 80 end elevation.

Figure 3 is a vertical transverse cross section taken at a point over one of the gins (not shown), and showing the construction and operation of the oscillating valve in receiving and delivering, the figure showing the position of the valve when receiving. 85

Figure 4 is a view similar to Figure 3, but showing the oscillating valve in the position assumed in discharging. 90

Figure 5 is an enlarged detail showing a side view of the valve operating mechanism and a rear face view of the gears therefor, and also showing the means on the larger gear for co-acting with an oscillating head 95 to impart oscillating movement to the valve.

Figure 6 is a detail showing the lower end of the telescope provided with a hinged agitating fork and shown swung out of operating position. 100

Figure 7 is an enlarged detail showing one of the valve padded abutments, and showing in dotted lines the wiping and rolling movement from one side to the other of the pad according to the direction of movement of the valve. 105

Referring to the drawings, 1 designates the usual telescope common to pneumatic elevators and designed to be used over the wagon loads of cotton arriving at the gin plants, which telescope forms a branch of the main pipe 8 that is also extended by the branch pipe 2, which receives cotton from a cotton storage house after the general practice, as when there are no wagons present for unloading, and this extension 2 is closed off by a gate valve 3, shown in dotted lines, that also closes the telescope 1 when the extension 2 is operating. The numeral 4 indicates a second telescope communicating with the pipe or conduit 8 and controlled by a gate valve 5, which is operated by the rod 6 to alternately close said telescope and the passage to the telescope 1. This second telescope extends down to the gin floor (not shown) that usually surrounds the upper part of the gin, and is designed to operate on the over-flow cotton that accumulates on the gin floor as a result of the continuous operation of the apparatus provided for by this invention, so that when for any reason the telescope 1 is not in operation, as when no wagon load is in position for unloading to the gin, the accumulated supply of cotton on the gin floor can be resorted to to keep the gins in operation.

The pipe or conduit 8 extends above a number of gins and is provided with a discharge passage-way 9, which enters a valve casing or chamber 36 that on its side opposite to the passage-way 9 is in communication through the passage-way 10, with the suction pipe 11 which directly forms a part of the pipe leading to the usual suction fan or blower 12.

Within the casing or chamber 36 a screen 12 is provided to collect the cotton drawn by the suction through the elevator conduit 8 by the pipe or conduit 11, and this screen is located within a cylindrical valve or barrel 13 mounted to oscillate within the casing in frictional contact with the inner edges of the passage-ways 9 and 10. This oscillating cylindrical valve is provided with a comparatively large opening 14 in its periphery and substantially in front of the screen 12, which extends slightly oblique to the opening 14 to bring it across the line of suction when the opening 14 is registering with the passage-way 9, as shown in Figure 3, in which view the valve is receiving cotton, and be substantially in line with the suction draft when oscillated through the discharging position, shown in Figure 4. Substantially opposite the opening 14 there is provided an opening 15 extending longitudinally of the valve cylinder, as does the opening 14, which opening 15 is designed to establish the suction draft through the valve 13 and its screen 12 while in receiving position, the opening 15 registering with the

passage-way 10, and when the valve is oscillated to close the passage 10, to then establish communication with the space within the casing 36 around the valve and with the outer air through the port 41, which immediately causes the suction to be broken within the valve so that the discharge of the cotton from the valve and off the screen will take place quickly.

Casing 36 at its lower end combines with a chute 16 through which the discharge of cotton is deposited within a gin feeder (not shown), after the usual practice.

As before stated, it is very common for the delivery chutes or hoppers in a battery of gins to become filled up so that the valves cannot continue to function, thereby impeding the elevation of the seed cotton. To avoid this a trough 17 is provided that extends along the series of chutes 16 and receives the over-flow cotton through an opening 18 at one side of the top of the chutes 16, and in order to automatically dislodge the surplus cotton between the valve and the chute-receiving opening after each discharging operation of the valve and force it through the opening 18 into the trough 17, a kicking board or wing 19 is attached to the underside of the valve at such a point as to cause it to sweep over the top of the chute during each oscillation of the valve to the opening 18 and during each of the returning oscillations of the valve after discharging to shove the surplus cotton in its path through the opening 18 into the trough 17, thus permitting the valve to continue to fill and discharge by reason of the removal after each discharge of each valve deposit of cotton.

For the purpose of collecting the over-flow cotton, a conveyer or belt 21 is provided that passes over pulleys mounted on shafts 20, the belt being provided with spikes to retain the cotton and assist in advancing the same. This conveyer forms a bottom to the trough 17 and delivers the over-flow of cotton to the telescope 4 where it accumulates on the gin floor. The conveyer belt 21 is driven from the line shaft 31 by a belt 32 running over the pulley 33 on the line shaft, and the pulley 42 on the conveyer shaft 20.

In order that the oscillating valve when in the receiving position (Figure 3) shall complete the closure of the casing thereby, a portion 34 of the casing 36 in the form of a removable board or abutment is affixed to the lower edge of one side of the casing adjacent to the opening 18, and extends into frictional contact with the valve. To provide for this frictional contact through a flexible yielding engagement there is provided upon the edge of the casing abutment 34, as well as on the like edges of the abutments forming the top and bottom of the passage-ways 9 and 10, valve engaging pads 35, which pads are preferably formed

by tacking over each of the said engaging edges a cloth strip in loose condition and stuffing the same with cotton lint to form a soft abutting contact for the surface of the 5 valve cylinder, so as to permit the pads to roll or move slightly with a wiping action at the beginning of each movement of the valve and in the direction in which the valve may be moving, as shown in Figure 7 10 in dotted lines.

In order that the pads 35 may be accessible for removal and repair, a long panel or side portion 38 is removable from the conduit 8 and may be held in position by means 15 of cleats 37, and the panel 39 in the conduit 11 be likewise removably held by cleats 40.

In order to oscillate the valve 13, the shaft 22 upon which the valve is mounted for oscillation in the casing 36 is rigid with 20 the valve and projects through the casing and is provided on its outer end with a channelled cross head or lever 23 to receive and be operated in one direction of oscillation by, a pin or stud 24 projecting from 25 the inner face of a gear wheel 25 journaled on a stub shaft 26 mounted on the side of the casing 36, the pin or stud 24 being arranged near the periphery of the gear 25 and with such relation to the lower 30 end of the channelled head 23, as to enter the channel thereof at one point of the rotation of the gear, and turn the head 23 in one direction to oscillate the valve to receiving position, the stud 24 describing an inward 35 and outward movement in the channel of the head and finally moving free of the head. After the head 23 has been moved into the position as shown in Figure 2, it is maintained in such position by the travel 40 of the segmental flange 27 which comes into engagement on its inner face with the lower end of the head, and prevents movement of the head until rotation of the gear takes the flange past the head, during which time the 45 valve is filling with cotton. When the limit of the flange 27 is reached, the stud 28 enters the channel head from the upper end and moves the head in the opposite direction very quickly to make a quick movement 50 of the valve to discharge the same, the head being then movably engaged by the outer face of a small segmental flange 29 to hold the same for a brief space in the discharging position when the operation of the 55 stud 24 is again brought into action. The studs 24 and 28 in moving the channelled cross head 23 each move in and out of the channel therein at its respective end of the cross head. As before indicated, there are 60 a number of valves to correspond with the number of gins, each having the mechanism above described for operating the same and in which the gear wheel 25 of each is driven by a small gear 30 mounted on the line shaft 65

70 lation to each other as to cause their discharge to take place successively so that at no time is the suction cut off from the elevator conduit by more than one valve, and then only for a very brief interval.

In order to facilitate the taking up of the cotton by the telescopes as they are moved about in the supply of cotton, there are provided forks or prongs 43, which are hinged adjacent the intake of the telescope and are adapted to be folded or swung into operative position against the end of the telescope and out of operative position on the outside thereof, the said forks having a front portion or bail 44 which forms a hand hold for manipulating the movable part of the telescope when the forks are protruding. By this means the seed cotton can be agitated in the act of moving the telescope over the supply of cotton and the cotton loosened 80 up so as to be more readily drawn into the telescope by the suction.

What is claimed is:

1. A pneumatic elevator for cotton gins, comprising a tube for elevating the cotton, 90 a suction tube, means for creating a suction therein, a valve interposed between the elevating tube and suction tube to alternately establish and close draft communication therethrough and receive the cotton from the elevating tube, and suction means arranged to operate on the overflow of cotton to subsequently re-introduce it into the elevator a delivery chute to receive the cotton discharged from the valve, and arranged 95 to permit the cotton to overflow and the valve to continue to discharge.

2. A pneumatic elevator for cotton gins, comprising a tube for elevating the cotton, 100 a suction tube, means for creating a suction therein, a valve interposed between the elevating tube and suction tube to alternately establish and close draft communication therethrough and receive the cotton from the elevating tube, a delivery chute 105 into which the valve discharges its collected cotton, means for automatically removing the surplus cotton as deposited when the chute is filled, and suction means for subsequently re-introducing the overflow cotton 110 into the elevator.

3. A pneumatic elevator for cotton gins, comprising a tube for elevating the cotton to the gin, terminating adjacent the ground in a movable receiving section, a 120 second tube for alternate operation terminating above an elevated floor about the gin and forming a branch of the elevator, a suction tube, and means for creating a suction therein and in the elevator tube, a 125 valve interposed between the elevator and the suction tube for alternately receiving and discharging the elevated cotton, means for conducting the cotton to the gin, and means for automatically removing accumu- 130

31. The valves 13 are so arranged with re-

lated cotton from the discharge opening of the valve to the vicinity of the intake of the said second elevating tube, whereby to permit the continued elevation and discharge 5 of cotton when a gin is over-supplied and the subsequent introduction into the elevator of the overflow cotton.

4. A pneumatic elevator for cotton gins, comprising a tube for elevating the cotton 10 to the gin, a second tube for alternate operation with the elevator, a suction tube, means for creating a suction therein and in the elevating tube, a valve interposed between the elevating tube and the suction 15 tube for alternately receiving and discharging the cotton from the elevating tube, means movable with said valve to pass back and forth to dislodge from the vicinity of the said discharge the cotton 20 as it accumulates whereby to deposit the same for re-introduction into the elevator.

5. A pneumatic elevator for cotton gins, comprising a tube for elevating the cotton to the gin, a second tube for alternate operation with the elevator, a suction tube, 25 means for creating a suction therein and in the elevating tube, a valve interposed between the elevating tube and the suction tube for alternately receiving and discharging 30 the cotton from the elevator tube, a wing extending from said valve and movable therewith to engage the cotton as it accumulates at the place of discharge of said valve, whereby to cause the same to accumulate and be re-introduced to the elevator by the second tube.

6. A pneumatic elevator for cotton gins, comprising a tube for elevating the cotton to the gin, a second tube for alternate operation with the elevator, a suction tube, 40 means for creating a suction therein and in the elevating tube, a valve interposed between the elevator and the suction tube for alternately receiving and discharging the cotton from the elevator, means movable with said valve to pass back and forth to dislodge from the vicinity of said discharge the cotton as it accumulates thereat, and a conveyer for depositing the overflow cotton 45 from a plurality of valves to the vicinity of the second tube for reintroduction to the elevator.

7. A pneumatic elevator for cotton gins, comprising a tube for elevating the cotton, 55 a suction tube, means for creating a suction therein, a casing interposed between the elevating tube and suction tube, having a cotton discharge opening, said casing being in open relation to the said tubes, a 60 valve for controlling the said communications, said valve having an opening adapted to alternately register with the communication opening to the elevating tube to receive cotton therefrom, and with the discharge opening of the casing, and an open-

ing adapted to alternately register with that establishing communication with the suction tube when receiving cotton and with an air inlet in said casing when discharging cotton, a separating screen arranged within said valve between the receiving opening and the suction outlet opening, and means for oscillating the valve to receive and discharge the cotton. 70

8. A pneumatic elevator for cotton gins, 75 comprising a tube for elevating the cotton, a suction tube, means for creating a suction therein, a valve casing connecting said elevating and suction tubes, and having a discharge opening, a hollow valve mounted to oscillate within said casing, having an opening to register alternately with an opening in the elevating tube and with the casing discharge opening, and an opening adapted to register with the suction port in the suction tube when receiving, a separating screen arranged between the said valve openings, and means for oscillating the valve to receive and discharge the cotton. 85

9. A pneumatic elevator for cotton gins, 90 comprising a tube for elevating the cotton, a suction tube, means for creating a suction therein, a valve casing connecting said elevating and suction tubes and having a discharge opening, said casing having extending therein from each tube a passage-way or extension in open relation with the casing, a hollow valve mounted to oscillate between said passage-way and to control the same and the discharge opening of the casing, 95 said valve having a screen mounted therein between the valve openings, and means for oscillating the valve to receive therein and discharge therefrom the cotton.

10. A pneumatic elevator for cotton gins, 100 comprising a tube for elevating the cotton, a suction tube, means for creating a suction therein, a valve casing connecting said elevating and suction tubes and having a discharge opening, a hollow valve mounted to 110 oscillate within the casing, said tubes having extensions thereof within the casing to abut the valve and to register with valve openings therein, said tube extensions having flexible contact pads at the valve abutting 115 edges to prevent the passage of air thereby when in contact with the valve, a screen arranged between the valve openings, and means for oscillating the valve. 115

11. A pneumatic elevator for cotton gins, 120 comprising a tube for elevating the cotton, a suction tube, means for creating a suction therein, a valve casing connecting said elevating and suction tubes and having a discharge opening, a hollow valve mounted to 125 oscillate within the casing, said tubes having extensions thereof within the casing to abut the valve and to register with valve openings therein, said tube extensions having flexible contact pads at the valve abutting 130

edges to prevent the passage of air there by when in contact with the valve, and a padded abutment forming a part of said casing to prevent air leakage under suction when the receiving valve opening is in position to bring the extension of the elevating tube into open relation with the casing through said receiving opening, and a screen arranged between the valve openings to arrest the cotton passing therein.

12. A pneumatic elevator for cotton gins, comprising a tube for elevating the cotton, a suction tube, means for creating a suction therein, a valve casing connecting said elevating and suction tubes, and having a discharge opening, a hollow valve for controlling said discharge opening, mounted to oscillate within the casing and having an opening to register alternately with an opening 20 in the elevating tube and the casing discharge opening, and an opening adapted to register with the suction port in the suction tube when the valve is receiving, a screen arranged between the said valve opening, 25 and abutment pads interposed between the said valve and the edges of the tube openings, and in fixed relation to said edges, said pads being adapted to be bent in the direction of the movement of the valve by contact therewith and under a rolling pressure.

13. A pneumatic elevator for cotton gins, comprising a tube for elevating the cotton, a suction tube, means for creating a suction therein, a valve casing connecting said elevating and suction tubes, and having a discharge opening, a valve mounted to oscillate 35 within said casing between said tube open-

ings, means for oscillating the valve, comprising a cross head adapted to be operated back and forth to oscillate said valve, operating means for said head, comprising a rotor carrying a stud adapted to slidably engage said head during a part of the revolution of the rotor to swing said head in one direction, and a stud adapted to similarly engage and operate said head from its opposite end during a part of the rotor's revolution to move said head in an opposite direction, and means for revolving the rotor.

14. A pneumatic elevator for cotton gins, comprising a tube for elevating the cotton, a suction tube, means for creating a suction therein, a valve casing connecting said elevating and suction tubes, and having a discharge opening, a valve mounted to oscillate within said casing between said tube openings, a cross head having a channel therein and adapted to be operated back and forth to oscillate said valve, operating means for said head, comprising a rotor carrying a stud adapted to enter and have relative movement within said head during a part of the revolution of the rotor to swing said head in one direction, and a stud adapted to similarly enter and operate the said head from its opposite end during a part of the rotor's revolution to move said head in an opposite direction, and means for revolving the rotor.
